(57) **CLAIM**

The ornamental design for a hook engagement member, as shown and described.

DESCRIPTION

FIG. 1 is a perspective view of the hook engagement member of the present invention;

FIG. 2 is another perspective view of the hook engagement member of FIG. 1;

FIG. 3 is another perspective view of the hook engagement member of FIG. 1;

FIG. 4 is a front view of the hook engagement member of FIG. 1;

FIG. 5 is a rear view of the hook engagement member of FIG. 1;

FIG. 6 is a right side view of the hook engagement member of FIG. 1;

FIG. 7 is a left side view of the hook engagement member of FIG. 1;

FIG. 8 is a top elevational view of the hook engagement member of FIG. 1; and,

FIG. 9 is a bottom elevational view of the hook engagement member of FIG. 1.

1 Claim, 8 Drawing Sheets
